UNITED STATES PATENT OFFICE

FRANZ MEYER, OF JENA, GERMANY, ASSIGNOR TO THE FIRM OF CARL ZEISS, OF JENA, GERMANY

GOVERNOR SWITCH FOR ELECTRIC MOTORS

Application filed November 19, 1927, Serial No. 234,473, and in Germany November 24, 1926.

The present invention relates to regulators of revolutions for electromotors in which a switch is actuated by the centrifugal force, which becomes operative at a flyball weight coupled to the electromotor and subject to the counteraction of springs.

According to the invention a particularly good working of these regulators and consequently a particularly uniform speed of the motor to be regulated may be attained if the flyball weight be rendered rotatable about a vertical axis and the countersprings be so constructed and disposed that their sagging direction falls into the direction of the axis of rotation of the flyball weight and that the centrifugal forces, arising during the revolution, do not cause a sagging of the springs transversely to the axis of rotation. One may attain in this way that the position of the movable part of the switch is almost only dependent upon the amount of the centrifugal force, operative at the flyball weights. Additional forces whose action upon the countersprings changes during each revolution and which may thus give rise to oscillations, are dispensed with in the new regulator. Such forces are not only for general reasons undesirable but, in addition, always difficult of predetermination with respect to their action and hard to be controlled. Owing to the absence of such forces the new regulator may be comparatively easily adjusted to a speed to be predetermined.

With the new regulator one may use as a counterspring, e. g. a cylindrical helical spring. In order to satisfy the above conditions, the said spring should be so disposed that its axial direction, which with such a spring coincides with the sagging direction, falls into the direction of the axis of rotation of the flyball weight, i. e. in particular in such a way that it coincides with the axis of rotation in order that the centrifugal forces, arising at the spring itself during the revolution, compensate each other and do not bring about a bend of the spring transversely to its axis, which would, of course, also vary the sagging of the spring.

A simplified suitable arrangement is at-

tained by choosing as countersprings platesprings which are so disposed as to lie, when the regulator is in an operative state, i. e. when they are in a stretched state, in a plane almost perpendicular to the axis of rotation of the flyball weight.

Figs. 1 to 3 of the annexed drawing show as an example a regulator according to the invention. Fig. 1 is a central sectional side view of the regulator. Fig. 2 is a cross section taken on line 2-2 of Fig. 1 and Fig. 3 is a detail section through the holding device of the flywheel weight. Fig. 4 represents a possibility of carrying out the electric connection of the regulator to the motor to be regulated and Fig. 5 shows a modification of the regulator represented in Figs. 1 to 3.

In the regulator illustrated in Figs. 1 to 3 there is vertically supported in a casing, consisting of a standard a^1 , a cylindrical jacket a^2 and a cover-plate a^3 , a shaft b , which carries at its lower end a bevel wheel b^1 and above thereof a disc b^2 . On this disc is fixed a little standard c in which is fastened a short band c^1 with one of its ends, while its other end is fastened to a bell-crank lever d . The latter is constructed as a cylinder whose axis coincides with that of the shaft b . On the upper part of the cylinder is fixed a horizontal band e^1 to which is joined a vertical metal band e^2 . On the band e^2 there is fastened a screw-bolt e^3 on which are screwed two nuts f^1 and f^2 , forming the flyball weight. These nuts are further held by a resilient metal band or plate g which is on the one hand screwed to the nut f^1 and on the other hand to a frame h , fixed on the disc b^2 . The band g allows small radial movements of the nuts f^1 and f^2 under the action of the centrifugal force. By such movements the body d is somewhat tilted in the plane of Fig. 1, the band c^1 thereby somewhat being bent. The bands e^1 and e^2 interposed between the body d and the screw e^3 form a connection allowing the said movements of the nuts f^1 and f^2 and of the body d to take place. At its lower end the cylinder d carries two knife edges d^1 with which it bears against two plate-springs i^1 and i^2 , resting on four knife edges i^3 , i^4 ... i^6 provided on the disc b^2 . Of

these knife edges those denoted by i^4 and i^6 are adjustable in elevation by means of screws j whereby the tension of the plate-springs can be varied. In the state shown the springs i^4 and i^6 have already sagged to such an extent as to be able to counterpoise the centrifugal force, arising at the flyball weight at the described speed of revolution. In order to avoid any relaxation of the springs, the disc b^2 is provided with a stop b^3 . The knife edges i^4 and i^6 which are carried by two little standards j' , are in addition displaceable with these standards by means of screws i^8 and i^9 as well as nuts i^{10} and i^{11} in the longitudinal direction of the plate-springs so that also the effective length of these springs may be varied and a satisfactory astatic condition be attained. At the lower front of the cylinder d is also fixed a lever d^2 , which forms the movable part of the switch to be actuated by the regulator. The fixed part of this switch forms a screw k , provided in a cross piece k^1 which is disposed and insulated in the frame h . In order to attain a safe current-supply for the switch, two collector rings l^1 and l^2 are fixed on the lower side of the disc b^2 on which rings slip two plate-springs m^1 and m^2 which are in their turn fixed on the standard a^1 . The springs m^1 and m^2 are supplied from outside with current by means of the mains m^3 and m^4 . The mechanical connection of the motor to be regulated with the shaft of the regulator takes place by a shaft n , which is provided on the one hand with a flange of coupling n^1 and on the other hand with a bevel wheel n^2 , engaging in the bevel wheel b^1 of the shaft of the regulator.

The electric connection of the regulator with the motor to be regulated may be seen from Fig. 4. The motor is connected to the mains q^1 and q^2 of a network while disposing a starter o^1 in front of the armature o and locating a regulating resistance p^1 as well as a stationary resistance p^2 in front of the exciting winding p . Parallel to the stationary resistance p^2 there is disposed the switch d^2 , k of the regulator, so that in a closed state it short-circuits this resistance and on being opened switches in the same. The mode of operation of the regulator may be easily gathered from the drawing. If the shaft b be rotated, the pressure of the knife edges d^1 upon the plate-springs i^1 and i^2 increases until the latter sag to such an extent that with the prescribed speed the two parts of the switch d^2 and k touch each other easily. Thereby the way is open to the exciting current through the resistance p^1 and over the switch d^2 , k whereby, however, the resistance of the branch current containing the switch is yet comparatively high. If, e. g. the number of revolutions then exceeds the prescribed value, the pressure, with which the two parts of the switch bear against each other, is increased, so that ul-

timately the resistance p^2 is completely short-circuited. Thereby the power of the exciting current is increased and the number of revolutions reduced until the relative pressure of the parts of the switch has once more attained the normal value.

As is obvious, a change in the sagging of the springs i^1 and i^2 can only be brought about by centrifugal forces, which are operative at the flyball weight f^1 , f^2 . Variations of the sagging by their own weight of the moved parts or by centrifugal forces, which become operative at the springs themselves, do not arise.

In the modified construction of the regulator according to Fig. 5 the two plate-springs i^1 and i^2 are replaced by a cylindrical helical spring r whose tension may be varied by a screw s .

I claim:

1. A speed regulator for electric motors, comprising a base member, a vertical shaft rotatably supported in this base member, means adapted to actuate this shaft, a frame connected to this shaft, a metal band fixed on the frame and on the flyball weight in such a way that its flat side lies vertically, a switch comprising two parts adapted to coact with each other, one of the said two parts being connected with the said flyball weight, while the other is connected with the said frame, springs disposed in the said frame in such a position that their sagging direction falls into the direction of the axis of the said shaft, and means adapted to transmit forces from the flyball weight onto the said springs.

2. A speed regulator for electric motors comprising a base member, a vertical shaft rotatably supported in this base member, means adapted to actuate this shaft, a frame connected to this shaft, a flyball weight, means for connecting this flyball weight to the said frame, these means allowing the flyball weight to move perpendicularly to the shaft, springs disposed in the said frame in such a position that their sagging direction falls into the direction of the axis of the said shaft, a bell-crank lever disposed in the frame and adapted to act on the springs, flexible metal bands between this bell-crank lever and the flyball weight, and a switch containing two parts adapted to coact with each other, one of the said two parts being connected with the said bell-crank lever while the other one is connected with the said frame.

3. A speed regulator for electric motors comprising a base member, a vertical shaft rotatably supported in this base member, means adapted to actuate this shaft, a frame connected to this shaft, a flyball weight, means for connecting this flyball weight to the said frame, these means allowing the flyball weight to move perpendicularly to

the shaft, springs disposed in the said frame in such a position that their sagging direction falls into the direction of the axis of the said shaft, a bell-crank lever disposed in the frame and adapted to act on the springs, two flexible metal bands arranged one behind the other and being disposed between the said bell-crank lever and the flywheel weight in such a manner that the flat sides of the one band are vertical and those of the other horizontal, and a switch containing two parts adapted to coact with each other, one of the said two parts being connected with the said bell-crank lever, while the other one is connected with the said frame.
